ALFRED CARLYLE DAY,
INVENTOR.

By *John M. Day*
his Attorney

UNITED STATES PATENT OFFICE.

ALFRED CARLYLE DAY, OF MELBOURNE, VICTORIA, AUSTRALIA.

ELECTRICAL SWITCH MECHANISM.

Application filed February 14, 1923. Serial No. 618,978.

To all whom it may concern:

Be it known that I, ALFRED CARLYLE DAY, a subject of the King of Great Britain and Ireland, residing at 8 Wright's Lane, Melbourne, in the State of Victoria, Commonwealth of Australia, have invented certain new and useful Improvements in Electrical Switch Mechanisms; and I do hereby declare the following to be a full, clear, and exact description of the invention, such as will enable others skilled in the art to which it appertains to make and use the same.

This invention relates to the use of a primary or electric light switch, and of — in series with or utilizing (except at the said switch) its circuit — a subsidiary circuit having any required switch, so that when the primary switch circuit is opened, the subsidiary circuit automatically comes into operation or becomes ready to be closed. The primary switch will often be a wall switch. I provide for it a casing which houses subsidiary circuit mechanism. The subsidiary circuit devices include series-choke, or resistance devices, for dimming the lamp or lamps provided; or such circuit will carry a pilot light, thermostat, testing points, and so on as found desirable. The construction I use is variable as to details; — its essentials are however made clear by the aid of the accompanying drawings, which indicate examples of what is usable.

In these drawings Figure 1 is a front elevation of my mechanism.

Figure 2 shows parts in Figure 1 but with the casing front cut away to exhibit interior.

Figure 3 is a side sectional elevation of Figure 1.

Figure 4 is a wiring diagram of Figures 1 to 3.

Figure 5 shows a modification of Figure 1, the primary switch being of rotary (instead of tumbler) type.

Figure 6 shows part of Figure 5, with part of the casing front cut away to exhibit the interior.

Figure 7 is a side sectional elevation of Figure 5.

Figure 8 is a wiring diagram of Figures 5 to 7.

Figure 9 shows, diagrammatically, a transverse section through Figure 7 in plan view.

Figure 10 is a front elevation of a modified casing.

Figure 11 is a side sectional view of Figure 10. Connecting wire conductors are omitted from various figures, but will be well understood.

Insulating material used will be heat resisting to suit the electric currents and wiring.

1 is a casing having fastening means as flange 2 with holes 3. This casing is fixable on any suitable support, and contains a space 4 for a primary or electric light switch, another space 5 for subsidiary circuit mechanism, and a space 6 for switch devices of the latter. These spaces ensure compactness which is in many cases important, but my invention is not limited to providing compactness, although the use of the casing promotes economy and time saving.

The casing has an aperture 7 through which projects, or is accessible, a control member, 8, of the light switch 9. The casing has another aperture 10 through which projects, or is accessible, the control member, 11, of the subsidiary circuit switch. I provide when desirable, a protective plate 12 at the casing back, as in Figure 3. The casing will be, for ventilation purposes, provided with louvres or openings, some only being illustrated at 1^a. Within the casing, insulated therefrom when the latter is of metal, are two electric conductors, shown as spring fingers 13, ends of which are shaped to suit the primary switch, that is the tumbler switch, of Figures 1 to 3, or the rotary switch of Figures 5 to 7. These conductors extend from terminals 14 of switch 9, to terminals 15 of the subsidiary circuit.

These conductors are, in Figures 7, 9, and 11, attached to an insulating plate 16, which is fixed to the casing at 17, and is apertured for wiring at 18. Wires of the subsidiary circuit pass through aperture 18, but are omitted in Figure 7; they extend through an insulating plate or base 19 to the contact points hereinafter mentioned.

The subsidiary switch control member or knob 11, of insulating material, carries an indicator shown as a pointer 20, the casing having relevant markings or wordings, such as Off—Low—Medium—High—Full on—for the guidance of the user.

An existing light switch casing could be removed to allow of adding my mechanism and using my method of circuit control.

Fingers 13 would be located contacting 5 with the terminals 14 and the switch control means 8 would project at 7.

In Figures 3, 4, 7, and 8, a rotary switch bar 37 is provided to control the circuits, its setting means being the knob 11.

- 10 The series-choke device (Figure 3) contains magnet elements 21 (having winding 22) and magnet elements 23, and insulating material 24, the latter constituting a base carrying a series of contacts A, B, C, D, E.
- 15 The conductors 13 are connected to (or are formed having) contacts A and B respectively; one lead 25 of winding 22 is connected to contact B, and the other lead 26 to contact E, tap wires 27 and 28 being connected to the contacts C and D respectively.

In Figure 8 the resistance elements have wires 29, 30, 31, each on an insulating strip (Figures 7 and 9) 32 having recesses or indented edges 33, the wires being set in the recesses and protected each by a folded housing 34 of mica or like insulating material, secured as by clips 35 on cheeks 36 (see Figure 9) fixed to the casing. The resistances are connected in series by leads. The lead 25 is connected to contact B, and the lead 26 to contact E; tap wire 27 is connected to contact C and tap wire 28 to contact D. The contacts are upon an insulating base 19.

As it contributes to safety, I locate resistance elements obliquely or vertically with air space around each so that heat they generate will escape upwardly, and 40 out of the casing at the back or through its ventilation apertures.

I also provide in the casing a heat de-

flecting asbestos partition 38 (Figure 7) which is in some cases faced with mica 39.

For brevity the subsidiary circuit may 45 be said to be open, where technically it would be described as short circuited by closing the primary circuit at 14^a.

When the primary circuit is closed it supplies the easiest path for the electric 50 current, which then leaves the subsidiary circuit inoperative; when any subsidiary circuit is energized, part 41 of the primary circuit will still be utilized and thus lamp 42 would be made to yield instead of a full 55 light a dimmed one according to the subsidiary elements used by positioning switch bar 37, various degrees of dimming being at will produced.

I claim:—

In electrical switch mechanism in combination a chamber casing having a front which is closed except for two spaced openings, the material around each opening being raised to accommodate projecting 65 portions of the mechanism, a primary switch located in said casing and a portion thereof extending through one of said openings, subsidiary circuit mechanism also located within said casing and a portion 70 thereof projecting into the raised portion and through said other opening, an insulating support overlying the latter mentioned raised portion on the inside of the casing, and spring contact fingers carried 75 by the insulating support and adapted to co-operatively co-act with said primary switch and said subsidiary circuit mechanism.

In witness whereof I have hereunto set 80 my hand.

ALFRED CARLYLE DAY.

Witness:

GEORGE G. TURRI.
